Attorney.

UNITED STATES PATENT OFFICE.

WILLIAM RAMAGE TATE, OF RIPPONLEA, NEAR MELBOURNE, VICTORIA, AUSTRALIA.

APPLIANCE FOR DELIVERING GASEOUS LIQUIDS.

1,412,321.

Specification of Letters Patent. Patented Apr. 11, 1922.

Application filed October 20, 1920. Serial No. 418,292.

To all whom it may concern:

Be it known that I, WILLIAM RAMAGE TATE, a citizen of the Commonwealth of Australia, and residing at 1 Myrtle Street,

5 Ripponlea, near Melbourne, in the State of Victoria, Commonwealth of Australia, have invented certain new and useful Improvements in Appliances for Delivering Gaseous Liquids, of which the following is a specification.

10 This invention has been devised in order to simplify the delivery apparatus and more effectively deliver the gaseous liquids contained therein at a uniform pressure.

15 Hitherto no effective and simple means have been employed whereby gaseous liquid in a container capable of discharging the whole or part of its contents has been so controlled that the pressure of gas is evenly 20 maintained until the last of the liquid content has been withdrawn.

By the means at present in use the first discharge of liquid is given at full pressure but subsequently owing to gas leakage 25 through the discharge, as in siphons, the liquid becomes flat and remains so until the siphon or container is recharged.

This invention has been devised in order 30 to overcome this defect and to provide mechanism combined with a siphon or other gaseous liquid container whereby on each withdrawal of liquid content from the container, the gas pressure on the liquid is replenished from the gas reservoir disposed 35 within the container, the valve mechanism being so arranged that immediately the pressure in the gas reservoir and the outer container is equalized, the control valve closes and does not reopen until the gas pressure

40 in the liquid container is reduced by the withdrawal of liquid, when the gas supply valve is automatically reopened by the pressure of a spring on a diaphragm controlling the valve and the gas flows under 45 pressure into the liquid container until the gas pressure in the gas reservoir and the liquid container is equalized at which period the downward or opening pressure of the spring is overcome and the valve is closed, 50 thus creating the condition that in lieu of an excess of effervescence on the first withdrawal of the liquid content an even discharge is given throughout the withdrawal of the whole liquid content of the container.

55 The essential characteristic embodied in

this invention is the combination and arrangement of the mechanical parts constructed and operating for the purposes specified.

In order that the invention may be more 60 readily understood it will now be described with reference to the accompanying drawing wherein the invention is adapted to a well known construction of delivery siphon.

The drawing shows the appliance in section.

According to this invention, the container 1 formed of glass or other suitable material is fitted with the usual siphon delivery tube 2, the top of which is normally closed by a 70 valve 3 disposed between the tube 2 and the delivery spout 4. The valve 3 is normally held to its seat 5 by a spring 6 disposed around the stem 7 between the valve 3 and the partition 8 in the tubular casing 9, the 75 top of which is closed by a cap 10.

The stem 7 is extended past the partition 8 and connects the usual control lever 11 provided with the usual finger pressure piece.

80 Arranged within the container 1 is a gas reservoir 12 the top of which is closed by the base 13 of a gas chamber 14 disposed in the path of the gas between the gas reservoir 12 and the container 1, a suitable gastight joint 85 being made by the washer 15 of rubber or other suitable material.

The member 16 of the gas chamber 14 threads as at 17 to the gas reservoir 12 and is jointed by the washer 18 to the top or 90 neck 19 of the container 1, and is further held by the ring 20 threading as at 21 to the flange 22.

95 This member 16 is formed with a circular ledge 23 receiving the diaphragm 24 which is held firmly in position by the top member 25 threading on the lower member 16.

The member 25 is domed or provided with a tubular extension 26 internally and externally threaded, the outer thread receiving 10 the cover or cap 27 while the adjustable nut 29 bears upon the inner surface of the cap 27. The nut 29 bears upon a spring 30 which is adapted to exert pressure on the diaphragm 24 by means of the spring 30, 105 and the cap 27 may be adjusted so as to vary the compression of the said spring.

110 This spring 30 is disposed around the stem 31 connecting at its lower end with the disc 32 seating on the diaphragm 24 while the

upper end of the stem 31 passes vertically and loosely through the nut 29 which acts as a guide.

Within the gas chamber 14 and resting 5 against the underside of the diaphragm 24 is a disc 33 between which and the base 13 of the gas chamber 14 is a helical spring 34 disposed around the valve stem 35 which connects at its upper end with the disc 33. 10 The spring 34 is seated in the recess 50 of a nut 51 threaded as at 52 to receive an adapter for recharging the gas reservoir 12 and also threading into a hole formed in the bottom 13 of the gas chamber 14. The lower 15 portion or bush 53 of the nut 51 provides for the passage of the gas and the reception of the valve stem 35 by the passage or port-way 36.

The spring 34 is disposed so as to exert upward pressure against the disc 33 and the valve stem 35 passes through the gas passage 36 in the base 13 and this gas passage 36 is common to both the gas reservoir 12 and the gas chamber 14.

25. The bottom of the gas passage 36 is normally closed by a valve 37 threaded or otherwise connected to the stem 35 and this valve 37 is recessed as at 38 to receive the rubber washer 39 which effectually makes a gas 30 tight joint when the valve is closed over the gas passage 36 and it will be readily understood that the bush 53 may be recessed to seat the top portion of the rubber washer 39 if desired. The spring 34 therefore having an upward pressure and the pressure in the gas reservoir 12, this maintains the valve 37 closed and consequently no gas can pass from the gas reservoir 12 to the gas chamber 14 until the gas pressure in the container 40 1 is reduced and the spring 30 acting against the diaphragm 24 causes the latter to move downwardly at its centre and the valve 37 is thus opened and the gas flows from the gas reservoir 12 past the valve 37 through the 45 gas passage 36 into the gas chamber 14 and from thence has an unobstructed path through the pathway 40 into the container 1.

Immediately the gas pressure in the container 1 and the gas reservoir 12 is equalized, 50 the diaphragm 24 returns to normal position helped by the spring 34 and the valve 37

closes against its seat and remains closed until the gas pressure in the container 1 is reduced by the withdrawal of liquid content caused on the operation of the lever 11 and 55 the cycle is then repeated.

To fill the gas reservoir 12, the member 25 and diaphragm 24 is removed and a suitable adapter fitted to the threaded portion 52 of the nut 51 and when pressure is applied, the valve 37 opens and gas is fed to the reservoir 12. When sufficiently charged the valve 37 automatically closes and the adapter is removed, the parts 24 and 25 refitted and the apparatus is ready for use. 60 65

The diaphragm 24 may be fastened if desired in which case it would be preferable to affix the same to the top member 25 for convenience in recharging the gas reservoir 12.

Apparatus constructed and arranged and serving the functions above described will be of great utility in all forms of delivering gaseous liquids and the members 16, 25 and parts connected therewith may be disposed horizontally if desired without departing 70 75 from the spirit and scope of the invention.

What I claim as my invention and desire to secure by Letters Patent is—

In appliances for delivering aerated liquids, a liquid container, a gas chamber communicating with the container, a gas reservoir, a bush having screw-threaded engagement with the base of the said chamber and having a passage providing communication between the said chamber and the reservoir, 80 a threaded extension on the bush for attachment of a re-charging nozzle, a valve seat formed on the end of the bush, a diaphragm in the gas chamber, a control valve engaging said seat, a valve stem connecting the 85 valve with the diaphragm, and means for delivering the aerated liquid from the container, the mechanism being all connected to the liquid container by a single casting.

Signed at Melbourne in the State of Victoria, and Commonwealth of Australia, this 16th day of August A. D. 1920.

WILLIAM RAMAGE TATE.
